UNITED STATES PATENT OFFICE.

PETER BROWN, OF CHICAGO, ILLINOIS, ASSIGNOR TO CHANNELL CHEMICAL COMPANY,
OF CHICAGO, ILLINOIS, A CORPORATION OF ILLINOIS.

EXPANSIBLE MOP-HEAD.

1,249,895.

Specification of Letters Patent.

Patented Dec. 11, 1917.

Application filed January 2, 1915. Serial No. 87.

To all whom it may concern:

Be it known that I, PETER BROWN, a citizen of the United States, and a resident of the city of Chicago, in the county of Cook and State of Illinois, have invented certain new and useful Improvements in Expansible Mop-Heads; and I do hereby declare that the following is a full, clear, and exact description of the same, reference being had to the accompanying drawings, and to the numerals of reference marked thereon, which form a part of this specification.

This invention relates to an improved form of mop head adapted to receive attached thereto a well known type of oil mop fabric in a manner permitting ready detachment of the mop fabric when necessary for washing, and again admitting replacement of the mop upon the mop head in a simple manner. By this invention, it is only necessary to actuate a single member which contracts expandible members, thus permitting the mop fabric to fall away from the mop head. The mop fabric may be again attached upon the mop head by expanding the members to cause the mop fabric to be tightened and retained upon the mop head.

It is an object therefore of this invention to construct a device provided with expandible means grooved to engage a mop fabric and when expanded serving to tighten the mop upon the device, holding the same securely retained thereon for use.

It is also an important object of this invention to construct a device provided with expandible means actuatable into expanded position by toggle levers which move beyond a dead center position to prevent accidental retraction of said expandible members.

It is also an object of this invention to construct a device consisting of a base plate provided with expandible members pivoted thereto and with toggle levers connected to actuate the expandible members toward and away from one another and to hold the same in an expanded position to retain a mop fabric attached upon the device.

It is furthermore an important object of this invention to construct a device provided with expandible members actuatable by means mounted upon a fixed base plate to retain a mop fabric attached to the device, and with a handle socket member pivoted upon

the device to receive a handle attached thereto.

It is finally an object of this invention to construct an improved and efficient form of mop head provided with quick attaching mechanisms for a mop fabric used thereon, simple and easy to operate.

The invention (in a preferred form) is illustrated in the drawings and hereinafter more fully described.

In the drawings:

Figure 1 is a top plan view of a mop head embodying the principles of my invention, with a mop fabric attached thereon.

Fig. 2 is a similar view thereof showing the mechanism in contracted position with the handle socket and mop fabric omitted.

Fig. 3 is a detail section taken on line 3—3 of Fig. 1.

Fig. 4 is a detail section taken on line 4—4 of Fig. 2.

Fig. 5 is a central vertical section taken on line 5—5 of Fig. 1.

Fig. 6 is a bottom plan view of the device with the mop fabric detached.

Fig. 7 is a fragmentary detail section taken on line 7—7 of Fig. 3, with parts omitted.

Fig. 8 is a top plan view with the mop fabric detached of a modified form of construction.

Fig. 9 is a section taken on line 9—9 of Fig. 8, with parts in elevation.

As shown in the drawings:

The device consists of a main or base plate 1, of oval shape and pointed at one end, and having integral ears 2, struck upwardly therefrom projecting vertically from the upper face of the base plate to afford a pivotal connection for a handle socket member 3, by means of rivets 4, engaged through said ears and through tongues 5, formed on each side of the handle socket member. An expanding mechanism for tightening a mop fabric upon the mop head is provided, which consists of a pair of similarly constructed members adapted to be spread apart from one another, and each comprising plates of metal 6 and 7, having curved or outwardly concave flange elements 8 and 9, respectively, formed on the outer margins thereof, and the shape of said members is such that the flanges thereof conform substantially to the curvature or outline of the base plate 1.

Said expandible members are connected to the base plate 1, by means of a rivet pin or stud 10, and for this purpose the upper plate 6, of one of the clamping members and the lower plate 7, of the other clamping member are cut away, so that said expanding members may lie flush with one another upon the base plate 1.

Near the rear end of each of said expandible members pins or studs 11, are secured thereto which engage through slots 12, in the base plate 1, said slots being of arc shape and concentric about the pivot pin 10, as a center. Also pivotally connected 15 upon the upper end of said respective studs 11, are actuating toggle links 13, which are each connected at their ends to a common stud 14, mounted on the end of an actuating link 15. For the purpose of operating said 20 actuating link 15, a plate 16, is provided, pivoted by means of a stud 17, upon the base plate 1, and disposed between the webs of the expandible members with the end of said actuating link 15, pivotally connected 25 eccentrically thereon. Said plate 16, is provided with an actuating handle 18, which, as clearly shown in Fig. 5, is bent upwardly to permit the same to swing over the web or plate 6, of either one of the expandible 30 members. The mop fabric for attachment upon the head consists of a plurality of strands of fabric 19, which, at their upper ends, are secured together by stitching and bound with fabric 20, thus affording a ring 35 or continuous closed loop adapted to be engaged around the mop head within the concave expandible members thereon.

In the modification illustrated in Figs. 8 and 9, I have provided a modified means of 40 operating the toggle links, and for this purpose the toggle links are connected at their ends upon a common pivot which is provided with an internally threaded head or nut 21. In place of the eccentric mechanism for actuating the toggle links, I provide a lead 45 screw 22, threaded through said head 21, and journaled in tongues of metal 23 and 24, struck upwardly from the base plate 1, there being a collar 25, secured on said lead screw 50 adjacent the tongue 23, and a knurled actuating head 26, on the end of the screw, which coacts with said collar, preventing longitudinal movement of the screw itself, although permitting rotation thereof.

55 The operation is as follows:

In order to detach the mop fabric from the mop head for the purpose of washing the mop fabric after the same has been used a considerable time, the handle 18, is swung 60 from the longitudinal position shown in Fig. 1, to a position such as shown in Fig. 2, thereby pulling inwardly on the toggle links 13, and retracting the expansion members, the flanges 8-9, of which engage the mop 65 fabric. Of course in connecting the mop

fabric upon the mop head the reverse operation takes place, that is the mop head is inserted within the continuous loop 20, of the mop fabric, and with the outwardly concave flanges of the expandible members of 70 the mop head loosely engaging the same. The handle 18, is then pulled around into a longitudinal position, thus causing the actuating lever 15, to thrust the toggle links 75 13, rearwardly past a dead center position, as clearly shown in Fig. 1, such position of the toggle links preventing an accidental retraction of the expandible members which maintain the mop fabric attached to the 80 mop head.

In the modified form of device illustrated in Figs. 8 and 9, the lead screw 22, serves the purpose of actuating the toggle levers 13, and of course the threads on said screw are of relatively large pitch, in order to secure a considerable movement of the threaded nut or head 21, when the lead screw is rotated. However, in the latter construction the expandible members may be adjusted apart to any desired position and will be 90 retained therein for the reason that the threaded connection is irreversible except when properly actuated by the knurled head 26. The pivoted handle socket member 3, as clearly shown in Fig. 7, permits an easy 95 use of the mop upon the floor or any article wherein the mop is moved toward and away from the person, the handle socket member 3, swinging with the handle and permitting the mop to lie flat in all positions.

I am aware that various details of construction may be varied through a wide range without departing from the principles of this invention, and I therefore do not purpose limiting the patent granted otherwise than necessitated by the prior art.

I claim as my invention:

1. In a device of the class described a base plate, grooved expandible members pivoted thereon, and links connected to said base 110 plate and to said members for actuating said members into expanded position to engage a mop fabric.

2. The combination with a continuous looped mop fabric of a mop head comprising a base plate, expandible means flatly disposed thereon and pivoted thereto adapted to expand within the loop of the mop fabric to firmly secure the same in position by expansion, a plurality of links connected 115 to said expandible means, and means connected thereto and to said base plate adapted to expand or retract said links when actuated.

3. In a device of the class described the 125 combination with a base plate of a unitary loop shaped mop fabric, horizontally expandible means pivoted on said base plate adapted to releasably engage said mop fabric, a lever mounted on said base plate, and 130

toggle links connected to said expandible means and said lever and adapted to be actuated by said lever to expand said expandible means.

5 4. In a device of the class described a base plate, a plurality of expandible members pivoted thereon, a handle socket pivoted on said base plate, toggle links connected to said expandible members, and 10 means to actuate said toggle links to expand said members away from one another.

5. In a device of the class described a mop head comprising a base plate, pivotally mounted horizontally expandible means 15 flatly disposed thereon adapted to be expanded to maintain a mop fabric upon the mop head, toggle links for actuating said means, a link mechanism connected to said toggle link for operating said toggle links 20 past a dead center position to prevent accidental retraction of said expandible means, and attaching means for a handle on the mop head.

6. In a device of the class described, a 25 mop head comprising a base plate, expandible members pivotally connected therewith, a toggle link on each of said members, a plate pivotally mounted on said base plate and an actuating link having one end there- 30 of connected to said toggle links and the other end thereof connected on said plate,

said plate adapted to operate said actuating link to move said toggle links past a dead center position and expand said members.

7. The combination with a looped mop 35 fabric, of a mop head comprising a flat base plate, expandible members pivotally connected with one another and to said base plate, a grooved flange on the outer edges of said expandible members affording a 40 channel surrounding said base plate, toggle links connected with said expandible members, and a lever connected with said links to expand said members to secure the mop 45 fabric against the flange.

8. The combination with a looped mop 50 fabric, of a mop head comprising a base plate, expandible members pivotally connected with said base plate, a grooved flange on the outer edges of said expandible members affording a channel surrounding said base plate, and means adapted to expand said members and to secure the mop fabric in the channel.

In testimony whereof I have hereunto 55 subscribed my name in the presence of two subscribing witnesses.

PETER BROWN.
